CLAIM

The ornamental design for a user interface for a portion of a display screen, as shown and described.

DESCRIPTION

FIG. 1 is a front view of a user interface for a portion of a display screen showing our new design; and,

FIG. 2 is an enlarged view of the claimed design illustrated in FIG. 1.

The broken line showing of various regions and the unshaded areas there within form no part of the claimed design. The broken line showing of the display screen in FIG. 1 is for illustrative purposes only and forms no part of the claimed design.
